UNITED STATES PATENT OFFICE

LOUIS ABT, OF CHICAGO, ILLINOIS, ASSIGNOR TO WILLIAM PADDOR, OF CHICAGO, ILLINOIS

SKYLIGHT

Application filed August 3, 1929. Serial No. 363,326.

My invention relates to automatic skylight control and although suitable for use with various types of ventilators, is especially adapted for use in the operation of ventilating skylights similar to that illustrated and described in my previous application, Serial No. 175,020, filed March 14, 1927, patented July 22, 1930, No. 1,771,107.

One of the objects of my invention is to provide an automatic skylight control by means of which the skylight sections, often extending many feet in length, may be automatically operated as a unit.

Another object is to provide a skylight control in which the movement of the skylight sections is automatically controlled relative to the temperature of the room.

A further object is to provide a thermostatically controlled ventilator operating means which may be adjusted to operate at any predetermined room temperature and in which the ventilators may also be controlled at all times by an operator at a distance.

Further objects will appear from the description and claims.

In the drawings in which an embodiment of my invention is shown:

Figure 1 is a vertical transverse section through a skylight construction, the operating means and control panel being shown in elevation;

Fig. 2 is an enlarged transverse section showing a part of the transmission;

Fig. 3 is a vertical sectional view illustrating the position indicating means;

Fig. 4 is a front elevation of the distance control switch; and

Fig. 5 is a diagrammatic view of the wiring and associated electrical devices.

Referring to the drawings in detail the construction shown therein comprises truss members 10 between which the ventilating skylight members 11 and 11a are pivoted on the fulcrum members 12 which are in turn secured to the truss members 10.

The skylight sections 11 and 11a, which may be of any desired length, are operated by means of motors 13 and 13a. In the present instance the motors are mounted on the cross beam 14 and a transmission is provided

between each motor shaft and the upper edge of its corresponding swinging skylight section. The transmission system comprises a worm 15 directly connected to the motor shaft and driving the worm gear 16 which is mounted on the shaft 17, a driving friction wheel is also secured to the shaft 17 and engages a suitable driven friction wheel 19 on the counter-shaft 20, the counter-shaft being provided with sprockets 21 engaging the racks 22 which are pivoted at 23 near the upper end of their corresponding skylight sections. The racks are held in engagement with the sprockets 21 by means of the yokes 24.

The motors are reversible, each being provided with a running winding and a starting winding, the direction of rotation being controlled by the polarity of the E. M. F. delivered to the starting winding.

Pole changing switches 25 and 25a are provided for the motors 13 and 13a respectively and are automatically controlled to reverse the direction of current to the starting winding when the skylights, in their movement, have reached the fully open or closed position.

In order that the switches 25 and 25a may be automatically reversed, cables 26 are secured to the upper edge of the movable skylight sections and are held taut by means of the weights 27. Members 28 and 29 are secured to the cables and so positioned that when the skylights are closed the members 28 will engage the pole changing switch arms 30 holding them in raised position, and when the skylights are fully opened the members 29 engage the switch arms 30 moving them to the position shown in dotted lines and reversing the polarity of the starting winding connections.

The friction drive included in the transmission prevents injury to the motors or skylights in case the members 28 and 29 are not accurately adjusted to operate the pole changing switches at the extreme open and closed positions of the skylights.

The worm drive provides a self locking construction to hold the skylight rigidly in any position.

The motors are automatically controlled by means of the thermostat 31 which is the ordinary thermostat of commerce and which is manually adjustable to make certain electrical contacts at any predetermined room temperature.

The thermostat may be placed in any desired location and is shown in the drawings mounted on a suitable panel board 32 together with certain manually controlled switches.

The thermostat may be adjusted so that when the room temperature reaches a certain predetermined degree the motors will operate to open the skylight sections, and when the room temperature drops below a certain predetermined degree the motors will operate in the reverse direction to close the skylights.

The method of electrically connecting the various devices to accomplish the desired results is diagrammatically illustrated in Fig. 5 and will be described later.

It will be evident from the description to follow that any number of motors may be controlled from a single thermostat although, for purposes of illustration, only two have been shown.

Switches 33 and 33a are provided for disconnecting either or both of the motors 13 and 13a respectively from the control circuit. This is especially desirable when it is necessary to repair the motor or any of the movable parts connected therewith.

In order that the movement of each of the skylights may be controlled by an operator independently of the thermostat control, suitable motor controlling switch mechanisms and indicator mechanisms are provided. The switch mechanism comprises manually operable pole changing switches 34 and 34a respectively. One of these switches is illustrated in Fig. 4, the controlling lever 35 of which is normally held in neutral position by a centering spring 36.

If the operator wants to open the skylight he moves the switch lever 35 to the mark R on the switch dial which will cause the motor to operate in a direction to open the skylight, if the operator wishes to close the skylight he moves the switch lever to the mark L on the dial causing the motor to operate in a reverse direction to close the skylight. The neutral centering spring prevents the operator leaving the motor running after releasing the switch lever.

A master double throw switch 37 is provided for disconnecting the thermostat control when it is desired to operate the motors and associated skylights by means of the manually operated switches. When the switch lever is in the raised position shown in Fig. 1 the circuit is so arranged as to provide for thermostat control and the switches 34 and 34a are ineffective.

When the switch lever

is thrown down to the opposite position the circuit for the thermostatic control is broken and connections are made so that the motors may be controlled by means of the switches 34 and 34a.

It is necessary that the operator should know the exact position of either of the skylight sections so that they may be moved to any desired degree between open and closed at any time. To accomplish this the indicator mechanism shown in Figs. 1 and 3 is provided and comprises a cylinder 38 having a piston 39, the piston rod 40 being connected to the movable skylight section by means of the connecting rod 41. The cylinder is connected with a bent tube indicator 42 by means of a flexible fluid conduit 43, suitable fluid being used for transmitting movement from the piston to the indicator. The indicator is calibrated to correspond with positions of the skylight sections.

In the wiring diagram illustrated in Fig. 5 all of the wiring and associated devices are shown diagrammatically, the main line wires from which the power is obtained being shown by the extremely heavy lines 44 and 45. The ordinary 110 volt lighting circuit is suitable for this purpose.

Each motor is provided with a running winding 46 and a starting winding 47. The wiring for the thermostatic control of the running winding is shown in heavy lines. The wiring for the starting winding is shown in ordinary light lines and the wiring for the operator controlled pole changing switches 34 and 34a is shown in very light lines.

In the diagram the motors are shown wired in multiple to be operated simultaneously, therefore a description of the means for operating one of the motors applies to the other.

The contacts in the thermostat are not adapted to carry sufficient current to operate the motors, and a relay is used in conjunction with the thermostat to close the switches 49 and 50 and connect the motor circuits to the source of E. M. F.

The master switch 37 is provided with the switch blades A, B, C, D, E, and F for closing the thermostatic control circuits when in a raised position, and when the switch is thrown down the blade A cooperates with the contact A' to close the circuit for controlling the motors by means of the switches 34 and 34a, the rest of the circuits being broken.

The thermostat 31 is provided with the contacts 51 and 52. When the room temperature reaches the highest predetermined degree to which the thermostat has been previously adjusted the contacts 51 close and the circuit is completed to operate the relay 48 which in turn closes the switches 49 and 50 and completes the circuits for operating the motors in a direction to open the skylight sections.

It will be understood that when the skylight sections are in the closed position, the switch

levers 30 of the pole changing switches 25 and 25a are in the raised position and the switch contacts 53 and 53a are closed and contacts 54 and 54a are open and when in this position 5 the motors can only be operated in a direction to open the skylights.

When the skylights reach the open position shown by dotted lines in Fig. 1, the pole changing switch levers 30 are automatically 10 forced downwardly by the means previously described and the contacts 53 and 53a are broken stopping the motors and leaving the skylights in the open position and at the same time contacts 54 and 54a are closed thus 15 changing the polarity of the motor circuits so that when the room temperature is reduced to a predetermined degree and the thermostat operates to close contacts 52 the motors are rotated in a direction to close the skylights, 20 the process being repeated indefinitely to maintain an approximately uniform room temperature.

The levers 30 of the pole changing switches 25 and 25a also operate the contacts 55, 55a 25 and 56, 56a which are alternately opened and closed with the pole changing contacts and serve to switch the thermostat circuit from high to low temperature control, that is, when the pole changing switch levers are raised and 30 contacts 53, 53a and thermostat contacts 55 and 55a are closed the motors are controlled by the high temperature contacts 51 of the thermostat to open the skylights, and when the pole changing switch contacts 54, 54a and 35 the thermostat contacts 56, 56a are closed the direction of rotation of the motors will be controlled by the low temperature thermostat contacts 52 to close the skylights.

Starting from the positive line wire 45 the 40 thermostat circuit, when the pole changing switches 25 and 25a are in the raised position, is through the wire T, including the master switch blade A, thermostat contact 51, branch T1, through contacts 55 and 55a, through wire 45 T3 including the master switch blade F, thence through the relay 48 and the return wire T4 completing the circuit to the negative line wire 44.

The operation of the relay 48 closes the 50 switches 49 and 50 and the running winding circuit is completed from the positive line wire 45 through T, relay switch 50, wires R to the running winding 46 and returning through R2, relay switch 49 and return wire 55 T4 to the negative line wire 44. At the same time the starting winding 47 of motor 13 is energized from the wires R and R2 through the pole changing switch 25 to the starting winding through the wire S, including the 55 master switch blade B, and returning through the wire S1 including the master switch blade C.

When the pole changing switches are thrown downwardly to reverse the starting 60 winding connections, the contacts 55 and 55a

of the thermostat branch circuit T1, are broken and contacts 56 and 56a are closed connecting the low temperature branch T2 to the wires T3.

An exactly similar circuit is used from the 70 pole changing switch 25a to energize the starting winding of the motor 13a, the wires S and S1 from the pole changing switch 25a, including the switch blades E and D respectively. 75

When the master switch 37 is thrown downwardly the above mentioned circuits are broken and the switch blade A cooperates with the contact A' to connect the manually operable switches 34 and 34a to the positive 80 line wire 45 through the wire 57.

If it is desired to operate motor 13 by means of the switch 34, in the direction to open the skylights, the controlling lever 35 is turned to the mark R thus electrically connecting the wire 57 through the switch blade member 58 to the starting winding wire S1, and the wire R of the running winding, the circuit for the starting winding being completed from wire S through switch blade member 59 to the negative line wire 44, the running winding circuit being completed from the wire R2 through the blade member 59 to the negative line wire 44. 85 90

When the control lever 35 is moved to the 95 mark L the starting connections through the switch are reversed and the motors operate to close the skylights.

The connection and the operation for the 100 switch 34a for controlling the motor 13a are exactly the same as in switch 34, the connections being reversible through switch blade members 60 and 61.

The manually controlled operation of the 105 motors independently of the room temperature is especially desirable in case of storms, when the skylight sections on one side may be closed and remain closed through breaking the motor circuit by opening the switch 33 or 33a, while the other side may continue 110 to be under the control of the thermostat.

What I claim is:

1. An automatic skylight control comprising movable skylight sections, motors for operating said sections, transmissions between said motors and said skylight sections, means for automatically and electrically controlling the operation of said motors to open and close said sections to maintain an approximately uniform room temperature, and means operable by said sections to control the direction of movement of said sections. 115 120

2. A ventilator control comprising motors for opening and closing said ventilators, a relay controlling the motor circuits, a thermostat controlling the relay and having high and low temperature circuit control contacts, adjustable means connected to said ventilators and automatically controlled by the position of the ventilators for switching the 125 130

relay controlling circuit from the high to low temperature thermostat contacts.

3. A ventilator control comprising motors for opening and closing said ventilators, a relay controlling the motor circuits, a thermostat controlling the relay and having high and low temperature circuit control contacts, and adjustable means automatically controlled by the position of the ventilators for changing the direction of movement of said ventilators to correspond with the related high and low temperature thermostat contacts.

4. A skylight control system comprising a plurality of motors for simultaneously opening and closing a plurality of movable skylight sections, said motors being wired in multiple from a common source of E. M. F., a relay for controlling said motor circuits, a thermostat having electrical contacts to make and break said contacts at predetermined temperatures to control the operation of said relay, and manually operable multiple contact switches arranged for starting said motors in either direction.

5. A ventilator control comprising a ventilator, and a motor, a transmission between said motor and said ventilator, means controlling the direction of rotation of said motor to open and close said ventilator, said means comprising a thermostat to make and break electrical circuits at predetermined temperatures, a relay for closing the circuits to said motor when either of said thermostatically controlled circuits are closed, and a pole changing switch automatically controlled from said ventilator for changing the polarity of the current to said motor when said ventilator reaches the open or closed position, a switch controlled by the position of said ventilator for switching said relay circuit from one thermostat circuit to the other corresponding to the open or closed position of the ventilator, and a plurality of switches operable to start said motor in either direction.

6. A ventilator control comprising a motor for opening and closing said ventilator, a transmission between said motor and said ventilator, said motor having a running winding and a starting winding, the electrical circuits of said running winding and said starting winding being controlled from a source of E. M. F. through a relay, thermostatic means for operating the relay at predetermined temperatures, pole changing means automatically actuated by said ventilator for changing the polarity of the starting winding when the ventilator has reached its open or closed position, and a manually operable means for controlling the starting winding circuits to start said motor in either direction.

7. A control system for ventilators including motor actuated operating means for said

ventilators, and an electrical controlling circuit for the motors including pole changing switches actuated by said ventilators to change the polarity of the current and reversing said motors, a relay controlling the motor circuits, a thermostat for actuating the relay at predetermined temperatures, operator controlled pole changing switches for operating individual motors in either direction independently of the thermostat control, and a master switch for breaking the thermostatically controlled circuits and closing the operator controlled circuits.

8. A ventilator control comprising movable skylight sections, motors for operating said sections, transmissions between said motors and said sections, a relay controlling the motor circuits, a thermostat controlling the relay and having high and low temperature circuit control contacts, means automatically controlled by the position of the sections for switching the relay controlling circuit from the high to the low temperature thermostat contacts, derived motor controlling circuits having manually actuated controlling means therein, and a master switch controlling all of the circuits and operable for disconnecting the thermostat control and connecting the derived circuits when it is desired to manually control the operation of the motors.

In witness whereof, I have hereunto subscribed my name.

LOUIS ABT.
